UNITED STATES PATENT OFFICE.

WALTER BRYANT NOYES, OF CHICAGO, ILLINOIS.

WOVEN-WIRE BED-BOTTOM.

SPECIFICATION forming part of Letters Patent No. 463,730, dated November 24, 1891.

Application filed January 26, 1891. Serial No. 379,022. (No model.)

To all whom it may concern:

Be it known that I, WALTER BRYANT NOYES, a citizen of the United States, residing at Chicago, in the county of Cook and State of Illinois, have invented a new and useful Improvement in Bed-Bottoms, of which the following is a specification.

This invention relates more especially to bed-bottoms which consist of woven-wire fabric, canvas, or other flexible material, and which are provided with means for applying a variable tension to the bottom in accordance with the weight to be supported by the same.

15 The object of my invention is to provide the bed-bottom with a device of simple construction for stretching the same, whereby its tension may be readily adjusted, and also to construct the stretching-rollers in such a manner that they serve to connect the side rails of the bed-bottom frame.

In the accompanying drawings, Figure 1 is a longitudinal section of my improved bed-bottom. Fig. 2 is a top plan view thereof, 25 partly in section. Fig. 3 is a detached perspective view of one of the adjustable hand-levers, the actuating-arm secured to the stretching-roller, and the spring connecting said arm and lever.

30 Like letters of reference refer to like parts in the several figures.

A represents the longitudinal rails or side pieces of the frame of the bed-bottom; and A' are cross-bars connecting the central portions 35 of the rails.

B B represent transverse stretching-rollers arranged at opposite ends of the frame, and C the wire fabric secured at its ends to the stretching-rollers. The wire fabric C is preferably supported between the stretching-rollers by spiral springs D resting upon the cross-bars A'. The stretching-rollers are each provided at both ends with a hollow cylindrical pivot or journal b, which is formed on a cap 40 b', secured to the end of the roller. This pivot or journal turns in a socket or bearing formed in the side rail, and is held therein by a screw d, passing through the rail and the central bore of the journal and entering the wooden 45 roller, as represented in the sectional portion of Fig. 2. The screws d, in opposite ends of each stretching-roller, hold the journals of

the roller in their sockets and also serve to draw the rails toward the end of the roller, thereby causing the rollers to act as cross-pieces for connecting together the ends of the rails, preventing spreading and warping of the rails and dispensing with separate bars for this purpose. The journal-sockets are made of less depth than the length of journals to prevent binding of the ends of the rollers against the inner sides of the rails.

E represents actuating-arms formed on or secured to the caps b' on the under side of the stretching-rollers, and F are adjustable hand-levers pivoted to the inner sides of the rails and which are each connected with the adjacent actuating-arm by a spiral spring g. The spring g is, preferably, detachably connected to a hook f formed on the hand-lever above its pivot. Each hand-lever is provided on its inner side with a projecting stud or pivot h, which is removably seated in one of a series of openings or sockets h' formed in the inner side of the rails A at different distances from the stretching-rollers.

In stretching the fabric of the bed-bottom, the pivot of the hand-lever is placed in one of the openings h', with the handle or long arm f' of the lever in an elevated position, as 80 represented by dotted lines in Fig. 1. Upon depressing the lever into the position represented by full lines in the drawings, the movement of the lever is transmitted to the actuating-arm through the connecting-spring g, 85 thereby turning the stretching-roller in the proper direction to stretch the fabric. The handle of the lever is held in a depressed position by engaging it under a screw or projection i, secured to the inner side of the rail, 90 the pivot of the hand-lever being of sufficient length to permit the lever to be partly withdrawn from its socket to clear the projection. After the lever has passed the projection its pivot is again pushed wholly into its socket. 95 The sockets of the pivot are preferably arranged obliquely or at a slight angle to the axis of the stretching-rollers, so as to render the pivot of the lever less liable to be withdrawn from its socket.

100 The spring g forms an elastic connection which permits the stretching-roller to turn to a certain extent when the wire fabric is depressed, while being sufficiently stiff to im-

part the movement of the hand-lever to the actuating-arm of the stretching-roller.

When it is desired to increase the tension of the bed-bottom, the adjustable hand-lever

- 5 is disconnected from the rail by withdrawing its pivot from the socket, and the pivot is placed in a socket farther removed from the stretching-roller. The lever is then depressed and locked in position by engaging it under 10 the projection, as above described. In this manner the tension of the body may be readily varied to comfortably support a heavy or a light person by simply shifting the adjusting-arm on the frame toward and from the stretching-roller, and the slack of the bed-bottom 15 may be conveniently taken up when necessary.

In the drawings two stretching-rollers are shown, each of which is provided at both ends 20 with an actuating-arm, hand-lever, and connecting-spring; but it is obvious that but a single stretching-roller may be employed and one end of the fabric secured to a stationary cross-bar of the frame.

- 25 *j* represents longitudinal supporting rods or wires which sustain the edges of the fabric between the stretching-rollers and prevent undue sagging thereof. These supporting-rods pass through the border of the fabric and are preferably secured at their ends to the end portions of the side rails A, on the upper sides thereof, as represented in Fig. 2, but, if desired, they may be secured to the stretching-rollers. Each supporting-wire is provided 30 at or near one end with a spiral spring *j'*, which causes the rod to contract and yield 35

lengthwise in accordance with the corresponding movements of the flexible bed-bottom. The spiral spring *j'* is preferably formed in one piece with the supporting-rod, as shown. 40 This construction reduces the cost of producing the rod and spring and avoids the formation of hooks or joints which are liable to catch in the bedding and tear the same.

I claim as my invention—

1. The combination, with the frame of the bed-bottom and a stretching-roller provided with an actuating-arm, of a hand-lever made adjustable on the frame toward and from the stretching-roller, a flexible connection unit- 50 ing the hand-lever with the actuating-arm of the stretching-roller, and a wire fabric or other flexible support attached at one end to said stretching-roller, substantially as set forth. 45

2. The combination, with a stretching-roller 55 provided with an actuating-arm, and the frame of the bed-bottom provided with a series of sockets or openings arranged at different distances from the stretching-roller, of an adjustable hand-lever having a pivot seated 60 in one of said sockets, a spring connecting the hand-lever with the actuating-arm of the stretching-roller, and a wire fabric or other flexible support attached at one end to said stretching-roller, substantially as set forth. 60

Witness my hand this 31st day of December, 1890.

WALTER BRYANT NOYES.
